UNITED STATES PATENT OFFICE.

ROBERT L. DENNISON, OF KANSAS CITY, MISSOURI.

ORE JIG.

Application filed January 10, 1927. Serial No. 160,272.

This invention relates to jigs or concentrators for the separation of crushed ores. It is the present practice to separate the more valuable metal bearing portions of ores from the cherts and other foreign matter by crushing the ores and subjecting them to the action of jigs which are more or less standard in construction and operation. These jigs usually comprise a plurality of cells each of which is divided into two compartments communicating with each other at their lower portions, one of the compartments being provided with a screen or grate for supporting the ore while a plunger is operable vertically in the other compartment for forcing water from the second named compartment upwardly through the grate or screen to lift and loosen the ore material whereby the metal bearing portions of the ore may settle upon the grate or screen by gravity. With such constructions, vertical reciprocation of the plunger obviously creates a suction upon its upward stroke which is substantially equal to the pressure exerted upon its downward stroke, and the ore lifted by the pressure stroke does not have the proper opportunity to settle by gravity inasmuch as the suction stroke of the plunger immediately draws the ore downwardly against the screen or grate. It also has been found that the operation of the plunger so greatly agitates the water, and consequently the ore, that the action of gravity is further interfered with. As a result of the disadvantages of such present constructions, it requires a considerable length of time for the metal bearing portions of the ore to settle by gravity, and the action at best is imperfect. It is an important object of the present invention to provide a water containing jig cell divided into compartments generally similar to the usual constructions, and to provide means for lifting the ore on the grate or screen by pressure and to release the pressure without creating any suction whereby the full effect of gravity is adapted to affect the ore to efficiently cause the separation of the component parts thereof. A further object is to provide novel means for effecting upward pressure of the water in the separating compartment in which the grate or screen is arranged without causing undue agitation of the water or ore, and to release the pressure without creating any

suction whereby the pressure action referred to is adapted merely to lift and loosen the constituents of the ore to permit the full force of gravity to effect the separation of the ore components.

A further object is to provide the lifting pressure referred to by intermittently admitting water under a suitable pressure head into the cell.

A further object is to provide novel means for controlling the admission of the water under pressure into the jig cell.

A further object is to provide means associated with the water admission means for varying the quantity of water supplied to the cell at each admission to control and vary the lifting action exerted upon the ore on the screen or grate.

A further object is to provide an apparatus of the character referred to comprising a plurality of cells of the character referred to whereby the ore continuously may be fed into one of the end cells and flow into and across successive cells whereby an efficient separating action is obtained and wherein, due to the efficiency of the apparatus, a greatly increased capacity is provided.

A further object is to provide an apparatus of the above mentioned character comprising a plurality of cells arranged in stepped relation and wherein the body of water in and above the cells is maintained at a substantially constant height to exert sufficient pressure upon the ore on the several screens or grates so as to minimize any agitating action which may be imparted to the water and ore through the admission of the water under pressure to the cells.

A further object is to provide means arranged adjacent the upper level of the water to collect those portions of the ore which are of such specific gravity as to permit them to float across the surface of the water.

A further object is to provide a plurality of cells of the character referred to which are separated by partitions, and to provide means for preventing the lodging of ore materials on the upper edges of the partitions during the operation of the apparatus.

Other objects and advantages of the invention will become apparent during the course of the following description.

In the drawings I have shown one embodiment of the invention. In this showing:

Figure 2 is a rear elevation.

Figure 3 is a vertical longitudinal sectional view through the apparatus,

Figure 4 is a section taken substantially 5 on line 4-4 of Figure 2,

Figure 5 is a detail section on line 5-5 of Figure 4,

Figure 6 is a similar view on line 6-6 of Figure 5,

10 Figure 7 is a detail perspective view of a portion of the valve operating mechanism,

Figure 8 is an enlarged sectional view showing the water admission mechanism and controlling means therefor,

15 Figure 9 is a section on line 9-9 of Figure 1 and,

Figure 10 is a similar view on line 10-10 of Figure 1.

Referring to the drawings the numeral 10 20 indicates the apparatus as a whole including front and rear walls 11 and 12 respectively. A dividing wall 13 extends longitudinally through the apparatus, as clearly shown in Figure 4. An inclined board 14 is

25 arranged in the lower portion of the apparatus and extends throughout the length thereof to deflect water introduced under pressure rearwardly of the wall 13 into the forward portion of the apparatus to exert

30 an upward lifting force on the ore beds, in a manner to be described. The apparatus is divided transversely by a plurality of partitions 15, as indicated in Figure 3, to form a plurality of jig cells, as will be apparent. The portion of the apparatus described is substantially of the usual construction and forms no part of the present invention except in combination with the elements to be described. A screen 16 is ar-

40 ranged in each of the cells forwardly of the wall 13, and these screens are arranged at progressively lower elevations from the inlet toward the outlet end of the apparatus, as will be apparent. A receiving hopper 17

45 is arranged adjacent the inlet end of the apparatus to receive the gangue dirt fed thereto through a suitable supply pipe 18. As in the usual constructions, this gangue dirt is fed into the apparatus together with a

50 sufficient quantity of water. The gangue dirt is adapted to pass into and over the successive cell compartments above the screens 16, and it is in these upper portions of the cell compartments that the separating action takes place. The screens 16 are sup-

55 ported upon suitable preferably wooden frames 19, and adjacent one side, each frame is provided with an inclined member 20 for a purpose to be described. Adjacent each

60 member 20 a plate 21 is arranged slightly spaced from the adjacent partition 15 and has its upper end 22 turned transversely across the upper edge of the partition. The lower end of each plate 21 extends below

65 the screens 16. Water is adapted to flow

upwardly between each plate 22 and the adjacent partition, and across the top of the latter to prevent the accumulation of ore materials on the upper edge of the partitions. While I have described the use of screens in each of the compartments, it will be obvious that suitable grates may be employed, but in practice screens have been found to provide the most advantageous results.

75 Adjacent the outlet end of the apparatus a relatively narrow transverse vertical compartment 23 is provided, this compartment being formed by the adjacent partition 15 and a vertical wall 24. The upper end of the wall 24 is provided with a vertically adjustable plate 25 mounted in a guide 26. Water is maintained substantially at the level indicated at 27, and this water level is governed by the position of the upper edge 85 of the plate 25. The water overflowing the plate 25 is adapted to pass into a narrow compartment 27' formed between the wall 24 and the end wall 28 of the apparatus. The lighter constituents of the ore are 90 adapted to float upon the surface of the water, and means are provided for collecting such light constituents. As clearly shown in Figure 3, a plurality of floatation troughs 29 extend across the apparatus from the front wall thereof to the dividing wall 13. Each of these troughs is provided with an inclined bottom as indicated in Figure 9 to move material from the front wall 11 whereby it may be discharged through a 100 suitable pipe 30, passage of the material from the pipe 30 being controlled by a suitable valve 31.

105 Means are provided for introducing pressure into the compartments rearwardly of the wall 13 to elevate and loosen ore on screens 16 to permit the heavier metal bearing portions of the ore to settle to the bottoms of the beds. Referring to Figures 3, 4, 5, 6 and 8, the numeral 32 designates an 110 auxiliary water supply tank connected to a plurality of depending pipes or conduits 33 corresponding in arrangement to the compartments formed rearwardly of the wall 13 and between the partitions 15. These pipes 115 communicate at their lower ends with the compartments through openings 34 whereby water may be introduced into the compartments to effect upward movement of the water in the compartments in which the screens are arranged. A valve casing 35 is arranged intermediate the ends of each of the pipes 33 and is substantially cylindrical as shown. A cylindrical valve 36 is mounted to oscillate in each of the valve casings, being supported upon a shaft 37. The valve is provided with opposite ports 38 which are adapted to align with the pipe 33 under conditions to be described. If desired, each pipe 33 and its associated valve casing may 125

be formed as an integral casting provided with flanges 39 at opposite ends, the upper flanges supporting the tank 32. Each shaft 37 is provided outwardly of the corresponding valve casing with a crank arm 40 having a pin 41 in its free end. Adjacent its outer end, each crank arm is provided with an upwardly extending pin 42 to receive the lower end of a compression spring 43. These 5 springs are adapted normally to swing the arms 40 downwardly to maintain the valves 36 in closed position as shown in Figure 6. A bracket 44 is secured to the rear face of the wall 13 adjacent each spring 43, and is 10 provided with an adjusting bolt 45 by means of which the tension of the springs may be adjusted. Each bolt 45 is secured in the bracket with which it is associated by nuts 46, a jam nut 47 being arranged against the 15 lower face of the lower nut 46. An adjusting nut 48 is arranged on the lower end of the bolt 45 and bears against the upper end of the associated coil spring. It will be obvious that tension of the spring readily may be 20 adjusted by moving the nut 48 vertically.

Adjacent each valve casing, an operating lever 49 is arranged, each lever being provided intermediate its ends with a cylindrical opening 50 in which is arranged an eccentric 30 51. Each eccentric is keyed or otherwise secured to a transverse shaft 52 supported in a suitable bearing as indicated at 53. The inner end of each shaft 52 is provided with a worm gear 54 rotation of which is 35 adapted to rotate the eccentric 51 for a purpose to be described. Each worm gear is adapted to mesh with a worm 55 carried by a shaft 56 journaled in suitable bearings 57, as clearly shown in Figure 8.

40 One end of each lever 49 is pivotally connected as at 58 with a link 59, the upper end of the latter being pivotally connected to one of the crank arms 40 by the pin 41 carried thereby. Beneath the link 59, each lever 45 49 is provided with a lug 60 which is adapted to contact with a bumper 61 to limit the downward movement of the inner end of the lever. The bumpers 61 are so arranged that when the springs 43 project the cranks 50 40 downwardly to their lower limits of movement the valves 36 will be in closed position.

Means are provided for depressing the outer ends of the cranks 49 to open the valves intermittently. As shown, a longitudinally extending shaft 62 is journaled in suitable bearings 63 adjacent the upper edge of the rear wall 12 of the apparatus, and this shaft is provided with a plurality of cams 64 corresponding in position to the 55 60 levers 49. Each of the levers is provided at its upper end with a roller 65 adapted to contact with one of the cams 64 as the shaft 62 revolves. The shaft 62 is adapted to be driven by a belt passing around a pulley 66, the shaft also being provided with

a free pulley 67 to which the belt may be shifted when it is desired to stop the rotation of the shaft 62. The positions of the pivots 58 are adapted to shift only as motion is imparted to the levers 49 by rotation of the 70 shaft 62, but it will be apparent that downward movement of the rear ends of the levers 49 will be determined by the positions of the eccentrics 51. For convenience in operating the eccentrics, the shafts 56 may extend through the apparatus and may be provided at their outer ends with operating wheels 68, as indicated in Figure 4. Rotation of either of these wheels obviously is 75 adapted to shift the position of the corresponding eccentric 51, thus changing the initial elevation of the rear end of the corresponding lever 49. The purpose of this operation will be referred to later.

Means are provided for taking off the 80 various metal bearing constituents of the ore from time to time as the settling operation progresses. It will be apparent that the smaller particles of the substantially pure metal may pass downwardly through the 85 screens into the lower portion of the apparatus, and as this metal accumulates it can be drawn off from time to time through pipes 69 controlled by gate or similar valves 70. The heavier portions of the metal which 90 are too large to pass through the screens may be drawn off through similarly valved pipes 71, these pipes communicating with the spaces above the inclined members 20, as shown in Figure 9. As will be understood 95 100 as the description proceeds, the drawing off of the ore materials causes the various strata of the ore bed to seek new levels, and consequently it will be understood that the shifting of the lower stratum will fill the space 105 above the member 20 as material is drawn therefrom. In order to draw material from the strata above that which finds its way into the space above the member 20, a preferably cast block 72 is arranged in the front 110 wall 11 of the apparatus adjacent each of the screens. The block 72 is provided with upper and lower tapered passages 73 and 74 which communicate with valved pipes 75 and 76 respectively whereby material will 115 be drawn from these passages.

In actual practice I prefer to employ five of the jig cells, and the actual separation of the purer metals takes place in the first three cells. Beyond these cells there is considerable material which contains valuable metals but which are not in a substantially pure form, and accordingly the valved pipes associated with the last two cells are adapted to draw the heavier metal containing constituents from the ore to permit it to be reground and returned to the apparatus for re-treatment. For the purpose of collecting the material from the last two cells, I prefer to provide a trough 77 as indicated in Figure 125 130

1. This trough is adapted to collect material from the last two cells and any suitable collection means may be employed for receiving the material flowing from the 5 trough.

As previously stated, a water tank 32 is preferably employed for supplying water to the cells to effect the elevation of the ore on the beds. A suitable pressure head is 10 maintained in the water within the tank 32 according to individual conditions, and the pressure of the water may be determined by a suitable pressure gage 78. If desired, the water may be supplied to the tank 32 15 by pumping it thereinto, but in practice I prefer to employ an upper main reservoir (not shown) communicating with the tank 32 through relatively large pipes 79. The elevation of the main reservoir will of course, 20 determine the pressure of the water delivered to the apparatus, and the tank 32 acts as a manifold for supplying water to the various pipes 33.

The operation of the apparatus is as follows:

The gangue dirt is fed into the hopper 17 through the pipe 18 in the manner previously stated, and from the hopper the material flows into the first compartment and upon 30 the screen therein. Obviously the continued feeding of material causes it to overflow the partitions 15, but as will be understood, most of the metallic constituents of the ore will be separated from the cherts and other foreign material within the first three compartments. It should be understood, however, that the invention is not in any sense limited to an apparatus employing a particular number of cells or to one in which the 35 principal separating action takes place within the initial cells, the conditions of separation depending partly upon the size and condition of operation of the apparatus and upon the material being used. As previously stated, the pressure head of water is 40 maintained within the tank 32 for exerting an upward pressure beneath the screens, and all the compartments are maintained full of water. The gangue dirt is fed into the apparatus with the usual quantity of water and 45 the level of the latter is maintained substantially at the line 27 as previously stated. As the shaft 62 revolves, the cams 64 intermittently contact with the rollers 65 to depress 50 the rear ends of the levers 49, thus elevating the crank arms 40 and swinging the valves 36 to open position with the openings 38 in alinement with the pipe 33. When the valves 55 assume an open position, the water under 60 pressure flows downwardly through the pipe 33 and into the rear compartments of the cells, from whence it flows downwardly and thence upwardly into the separators to exert 65 a lifting action upon the ore material on the screens. This action causes the water to

flow through the material thus elevating, separating and loosening it, as will be understood. Continued rotation of the shaft 62 then causes the cams to be released from the operating levers and the springs 43 act to 70

depress the crank arms 40 to close the valves 36 and cut off the supply of water. In this connection it will be noted that no suction means is employed as is true with the usual constructions, which employ plungers, and 75

the material on the screens is adapted to freely settle not only without suction but also without undue agitation, and gravity is adapted to exert its force upon the materials to cause a more efficient separating action whereby the heavier constituents of the ore freely settle toward the bottoms of the beds. The action referred to is repeated 80

successively during the rotation of the shaft 62, and substantially the same separating action takes place in all of the cells. As previously stated, however, the material which 85

finds its way into the last two cells usually is of such a nature that it must be reground and accordingly this material may be drawn 90

off through the valved pipes associated with the last two cells and collected from the trough 77. The finer particles of the metal pass through the screens 16 and may be 95

withdrawn from the cells through the valved pipes 69. The portions of the substantially pure metal which will not pass through the screens 16 may be drawn off by opening the valved pipe 71. The pipe 71 communicates 100

with the space above the member 20, and as material is drawn from this point, it will be apparent that the level position previously occupied by the lower stratum of metal will be destroyed. As the separating action 105

continues however, the stratum referred to tends to seek its own level, and accordingly additional material will be fed into the space above the member 20 from whence it may be withdrawn. In a similar manner the successive strata may be withdrawn from the 110

pipes 75 and 76, these strata also seeking their own levels as material is drawn from the pipes. The inclination of the member 20 serves to feed material toward the pipe 71, while the tapered passages 73 and 74 115 serve the same purpose with respect to the pipes 75 and 76.

As previously stated, the operating levers 49 are adapted to be actuated by the cams 64, and for given positions of the eccentrics 120 51, the valves will be opened a given amount to permit the passage of water therethrough. Under some conditions it is desirable to increase or decrease the amount of water fed at each opening of the valve, and accordingly the eccentrics are provided. When it is desired to decrease the amount of water supplied, either of the shafts 56 or any combination of them, may be rotated, thus effecting rotation of the worm wheels 54 through 125

the worms 55. The axis of each shaft 52 is fixed in its bearing, and accordingly rotation of either worm wheel 54 in a clockwise direction similarly rotates one of the cams 5 thus lowering the center of the cam. This action does not alter the position of the pivot pin 58, but lowers the rear end of the lever below its normal position. Consequently it will be apparent that when the roller 65 10 contacts with the cam associated therewith, there will be a smaller downward movement of the rear end of the lever, and consequently the valve will be opened to a lesser extent. Thus it will be apparent that the 15 supply of water at each opening of any of the valves may be governed according to the material which is fed into the apparatus.

It will be obvious that the various cells will be substantially filled with material, 20 and in actual practice it has been found desirable to prevent the accumulation of the ore upon the upper edges of the partitions 15. For this purpose I provide the plates 21, and also incline the upper edges of the 25 partitions 15 and the upper ends 22 of the plates 21. Each successive pressure impulse delivered to the cells causes a small quantity of the water to flow upwardly into the space between each plate 21 and its adjacent partition, and this water flows across the upper 30 edge of the partition beneath the end 22 of the plate, thus maintaining the upper edges of the partitions free of the ore material, and also assisting the movement of the material to successive cells.

As is well known, some of the constituents of ore are relatively light, being of such specific gravity that they will float upon the surface of water. Accordingly the floatation troughs 29 are provided, and these lighter constituents flowing with the current of water toward the outlet end of the apparatus, will be collected in the troughs 29 from whence they may be collected from 45 the valved pipes 30, as indicated in Figure 9.

The excess water fed into the apparatus overflows the plate 25 into the compartment 27 from which it may be withdrawn. The provision of the plate 25 maintains the water 50 at a substantial depth above the screens, thus preventing the creation of a water current across and within the upper portions of the cells, thus preventing valuable ore materials from being swept from the cells by the current of water. The maintaining of the water level at the point indicated also serves to maintain some pressure above the screens to assist in minimizing agitation of the ore 55 materials whereby they are adapted more readily to settle upon the screens. The chats

and other foreign material are adapted to pass from the last cell into the compartment 23 from whence they may be collected and passed to the tailings elevator for suitable disposal.

It is to be understood that the form of the invention herewith shown and described is to be taken as a preferred example of the same and that various changes in the shape, size and arrangement of parts may be 65 resorted to without departing from the spirit of the invention or the scope of the subjoined claims.

I claim:

1. Apparatus of the character described 75 comprising a tank having an inlet end and an outlet end, partitions dividing said tank into a plurality of cells each having forward and rear compartments communicating at their lower portions, perforate means arranged in each forward compartment for supporting a bed of ore, said perforate means and the upper edges of said partitions being arranged at progressively lower heights toward the outlet end of said tank, 80 said tank being provided with an end wall at its outlet end, a plate carried by said wall and vertically adjustable, said tank being adapted to contain a liquid to the level of the upper edge of said plate, means for 85 intermittently subjecting the liquid beneath said perforate means to pressure, and a plate arranged in the forward compartment of each cell toward the outlet end of said tank, each plate being arranged substantially parallel to and slightly spaced from the adjacent partition and having its upper edge extending partially across and slightly spaced from the upper edge of the adjacent partition and having its lower edge extending 90 below said perforate means, whereby water will flow from the space below said perforate means and over the upper edges of each partition to remove materials lodged thereon.

2. Apparatus of the character described 105 comprising a tank having an inlet end and outlet end and means for maintaining a current through said tank, partitions dividing said tank into a plurality of cells, ore-supporting means arranged in each cell, a plate carried by each of said partitions and spaced therefrom, said space communicating with the space below said ore-supporting means and with the upper edge of said partition 110 whereby materials lodged thereon will be removed when a current is directed through said tank.

In testimony whereof I affix my signature.
ROBERT L. DENNISON.
